JULIEN MARIE PIERRE FAURE, OF ST. ETIENNE, FRANCE, ASSIGNOR TO VERNEY-CARRON & CIE., OF ST. ETIENNE, FRANCE

FIREARM

Application filed October 10, 1927, Serial No. 225,158, and in France November 3, 1926.

The present invention relates to improvements in fire-arms with stationary barrels, and the improved fire-arms may be constructed as army rifle, fowling-piece or light gun of the single-barrelled or double-barrelled type.

One feature of the invention consists chiefly in the fact that the operations required for the unfastening of the mechanism, the opening of the gun, the removal of the cartridge shells, the cocking, and the closing and fastening, are effected by the displacement of a movable element or block which is slidable in guides upon a stationary plate.

A further characteristic of the invention consists in the means employed for the locking or fastening of the gun, which comprise one or more movable heads provided with threaded sectors coacting with like threaded sectors disposed in the respective bores of the socket piece, said movable heads being disposed in the said movable block and thus moving with the latter.

Another characteristic consists in the fact that all parts of the fastening device and the percussion device are disposed in the interior of the gun, either in the said movable block or in the bottom plate, whereby the gun will be perfectly smooth on the exterior, without projecting parts.

Further characteristics of the invention will be specified in the following description with reference to the appended drawings which are given solely by way of example, relating to a double-barrelled gun according to the invention.

Fig. 1 is a partial view in section on the middle plane, the gun being shown in the open position, with the cartridge shells removed.

Fig. 2 is a partial view in section on the axis of a tube, with the gun closed and ready for firing.

Fig. 3 is a partial external view.

Fig. 4 is a cross-section of the movable block and of the parts contained therein, on the line 4-4 of Fig. 1.

Fig. 5 is a cross-section of the gun on the line 5-5 of Fig. 1.

Fig. 6 is a cross-section on the line 6-6 of Fig. 1 with the breech closed.

Fig. 7 is a section on the line 7-7 of Fig. 1.

Fig. 8 is a side view of a movable head, and

Fig. 9 is a rear end view of the movable head.

Fig. 10 is a partial view analogous to Fig. 1, with parts broken away, showing a modified construction of a gun according to the invention.

Fig. 11 is another partial view, analogous to Fig. 2, of the said modification.

Fig. 12 is a corresponding external view.

Fig. 13 is a cross-section on the line 13-13 of Fig. 12.

Fig. 14 is a side view of a movable head comprised in said modified construction.

As observed in the apparatus shown in Figs. 1 to 9, the gun according to the invention comprises six essential parts: (a) the gun tubes and their assembling socket piece, (b) the base plate, (c) the movable block, (d) the bottom plate, (e) the wood portion, (f) the metal fittings.

The gun tubes 1 and 2 are screwed into the assembling socket 3, and they are connected together throughout their whole length by the middle strip 4 (Figs. 1 and 7). The two bores of the socket 3 corresponding to the two barrels 1 and 2 carry three respective screwthreaded sectors 5, 6 in the interior, and each sector covers $\frac{1}{6}$ of the internal circumference of the said bores. A recess 7 which is formed between the two bores and at the lower part of the said socket, serves to contain the extractor 8. The said socket carries at the lower part a boss 9 engaging a corresponding recess 14 formed in the base plate 11; into the said boss is inserted the screw 12 which secures the said socket to the plate 11, said screw being operated by means of the lever 13. A rib which is formed below the said socket and upon its entire length serves to secure the proper direction of the guns relatively to the plate 11 when the parts are assembled.

At the front part of the plate 11 is disposed the recess 14 for the boss 9 of the socket 3, as well as the rib which is formed below the said socket for the proper mount.

ing of the barrels. Upon the upper face of the plate 11 are provided two lateral slots 15 (Fig. 6) which serve as guides for the movable block. Suitable apertures are also provided for the insertion of the hammers 16 and 17. A downwardly extending front portion 18 serves for the insertion of the front end of the bottom plate 19. At the rear end of the said plate is formed the tapped hole coacting with the assembling screw 20.

The movable block or breech block comprises the main part 21 having at the bottom a T-shaped portion 22 (Fig. 4) which is slidable in the guiding slots 15 of the plate 11.

At the front part of the block 21 are formed two cylindrical recesses adapted for the insertion of the respective shanks 23 of the movable heads 24 (Figs. 8 and 9) which are adapted to enter the respective apertures in the socket 3.

Into a recess formed in the block 21 is inserted the member 25 which controls the rotation of the said movable heads. The middle part of the said block is cut out upon its entire height to afford passage to the device actuating the member 25 and also to allow the motion of the hammers 16 and 17. At the upper part of the block 21 are formed two flat parts 26 in which engage the lugs of the lever 27 actuating the mechanism.

The shanks 23 of the said movable heads are rotatable in their recesses but are held against lengthwise motion; for this purpose they are respectively provided with a stud 28 which is slidable in an annular groove formed in the respective recesses. In each of the said shanks is formed a fastening ramp 29. The movable heads 24 carry the threaded sectors 30 coacting with the like sectors of the socket 3. At the rear end of each shank 23 is formed a slot 31 termed safety slot, in which is engaged the corresponding hammer which thus strikes against the striker 32, for the firing position.

In the contrary case, i. e. should the rotation of the movable heads in the socket 3 be incomplete, each slot will have an inclined position, and this will prevent the respective hammers from making contact with their strikers. Each movable head, with its shank, is pierced with an axial bore which contains the movable striker.

The rotation of the movable heads for the fastening of the device in the bores of the socket 3 is effected by a mechanism comprising a member 25 of parallelopipedon shape provided with two lateral trunnions 33 (Fig. 4) engaging the fastening ramps 29 of the shanks 23; said trunnions also limit the lengthwise motion of the strikers 32 in the movable heads, and for this purpose each striker has a restricted part as shown in Fig. 2.

At the front part of the member 25 is formed the lower projection 34 which serves as an abutment for the spring 35 which is contained in a recess in the block 21 and which urges the said member 25 towards the front.

The longitudinal motion of the member 25 is controlled by a jointed device which comprises a link 36 pivotally mounted at 37 in a forked portion of the member 25 and at 38 upon the controlling lever 27; said lever is pivoted about a pin 39 secured to the movable block 21 and comprises a long arm whose end is provided with lugs coacting with the flat parts 26, and also a short arm 40 whose outer end carries a roller 41 which during the whole of the opening and closing strokes of the block 21 will slide upon the plate 11 and will thus prevent the lever 27 from descending; it can only descend when the roller 41 can enter a recess in the said plate. Since the spring 35 urges the member 25 forwardly, the said controlling lever will operate in an approved manner during its entire stroke.

It will be observed that the pivotation of the lever 27, by moving the member 25 lengthwise, will act—due to the trunnions 33 engaged in the ramps 29—to effect the rotation of the said movable heads; said ramps are so disposed that this rotation will take place over $\frac{1}{6}$ revolution, and in this manner the sectors 30 of each movable head will come into engagement with the corresponding sectors 5 or 6 of the socket 3, or on the contrary will be released therefrom, according as the device is to be fastened or unfastened. As above observed, the lever 27 can be operated only when the block 21 is in the closing position.

The extractor 8 which is slidable in the plate 11 is drawn along with the movable block 21 by means of a projection 42 on the bottom of the block, and this also limits the opening stroke of said block, by the use of an abutment (not shown) formed on the plate 11; said abutment also limits the motion of the extractor during the opening movement.

The bottom plate 19, whose front projection engages the vertical part 18 of the base plate, and which is secured at the other end by the assembling screw 20, comprises two lateral cheeks; below the bottom plate 19 is riveted the bow 43 which protects the triggers 44 and 45, the latter being engaged in suitable cut-out parts of the bottom plate 19.

Between the cheeks of the bottom plate 19 are disposed the hammers 16 and 17; said hammers are mounted on an axle 46, and their respective central portions are provided with projections 47 (Figs. 1 and 2) coacting with the safety device, and further comprise an abutment 49 for cocking purposes. The triggers 44 and 45 are movable on the axle 48; each trigger is provided at the upper part

with the forwardly-situated cocking portion 50, and the rearwardly situated flat portion coacting with the trigger spring 52. Herein the said springs are of the kind commonly known as rat trap springs; the said springs are mounted on the axle 46 and are cocked in the overturned position of the hammers 16 and 17 (Figs. 1 and 2). The said hammers are released by pulling the said triggers so as to disengage the abutments 49 from the ends 50.

The safety device comprises the lever 53 secured to the cam 54; said lever is disposed on one side of the gun, and when it is turned about it will hold the central parts of the hammers. A suitable spring 55 serves to secure the mechanism in the firing position or in the safety position.

The wood portion of the gun is made in two pieces, i. e. the gun stock which is held by assembling screws, and the front piece which is screwed to the bottom of the plate 11.

The metal fittings are of the usual type employed in fire-arms.

The operation of the gun, which has been described by way of example, is as follows: Let it be supposed that the shot has been fired. The gun is opened by raising the operating lever 27; the member 25 which is connected with the said lever by the link 36 will be thus moved to the rear, and will turn the movable heads through $\frac{1}{6}$ revolution, as above stated. The sectors 30 of said heads will thus be released from the corresponding sectors 5 or 6 of the socket 3, thus unfastening the mechanism. The movable block 21 is thus enabled to slide to the rear of the plate 11 and draws with it the said movable heads. In this motion of the block 21, the hammers 16-17 are overturned on their axle into the cocked position, the trigger springs being thus compressed.

At a certain point on its stroke, the extractor 8 which is drawn by the projection 42 of the block 21, will move to the rear and thus extracts the cartridge shells.

New cartridges can then be placed in the barrels, and the said movable block 21 is moved forwardly by the lever 27 until the said movable heads made contact with the ends of the cartridge. The roller 41 may now engage the corresponding slot in the plate 11, and the lever 27 can then be lowered, as above stated. Due to this motion, the member 25 rotates the movable heads whose threaded sectors 30 now engage the like sectors of the socket 3. The gun is thus closed and fastened when the lever 27 is completely lowered.

To hold the movable heads against rotation during the motion of the block 21 upon the base plate, the lower tenons of the said heads preferably comprise a very long bevelled part (not shown), and when the gun is opened, this part makes contact with the

plate 11, so that the movable heads will be prevented from rotating.

The engagement of the roller 41 in the corresponding slot in the plate 11 will preferably take place somewhat before the complete engagement of the movable heads in the socket 3, so that the lever 27 can be lowered somewhat sooner, and in this manner any of the cartridge shells that may be accidentally out of shape can however be moved forward in the gun barrels; to this end, the fastening ramps 29 of the shanks 23 of said heads comprise a straight part, as shown in Fig. 8.

Obviously, the invention is not limited to the above described construction which may be variously modified without departing from the principle of the invention.

For instance, the gun may be obviously constructed as a single-barrelled gun.

Figs. 10 to 14 relate to a modification which differs from the one represented in Figs. 1 to 9 chiefly in the construction of the fastening mechanism. The movable block 121 is made hollow in the interior for the insertion of the hammers 16-17, and said element comprises two recesses at the front, in which are placed the shanks 123 of the movable heads 124.

The said shanks 123 may be given a helical motion in their recesses, in either direction, and to this end they are each provided with a helical fastening ramp 129 in which is permanently engaged a stud 133 screwed into the block 121. Each stud 133 limits the motion of the corresponding striker 132 which comprises for this purpose a restricted part (Fig. 11). The heads 124 are provided with threaded sectors 130 coacting with like sectors in the interior of the socket 103. Each shank 123 comprises, as before, a safety slot 131.

At the respective sides of the block 121 are disposed the striated buttons 156-157 which are mounted on the ends of the respective horizontal studs 158-159, these being outwardly urged by the spring 160 (Fig. 13). On the said studs are mounted the respective stops 161-162. In the closing position, said stops engage the guiding slots 115 of the base plate 111 and thus hold the block 121 upon the said plate. This locking device serves to prevent all separation of the element 121 from the socket piece under the effect of jarring. The movable block can be released, so that it may slide upon the plate 111, by pushing in the buttons 156-157, thus releasing the stops 161-162 from their recesses.

The operation of the said fastening mechanism is as follows:

During the motion of the block 121 for closing purposes, the movable heads which are drawn with the said block will be engaged in the socket piece 103; the sectors 130 will be engaged in the spaces between the sectors of said socket piece. At this time, the said block being still pushed forward, it will be displaced relatively to the movable heads,

and the latter, due to the studs 133 engaged in the fastening ramps, will turn in their respective bores, and the locking is effected, while at the same time the stops 161—162 will hold the said movable block.

For unlocking the buttons 156—157 are first pushed in so as to release the movable block 121, and this latter is then brought to the rear. The heads 124 will turn so as to release the sectors from the socket piece, and are then drawn back along with the movable block.

The said modification is applicable with equal facility to single-barrelled or double-barrelled guns, but it is particularly adapted for the single-barrelled type, in which but little force need be exercised upon the movable block for the insertion of the cartridge or the removal of the shell, even should the shells be out of shape.

The mechanism comprising the control lever 27 shown in Figs. 1 to 9, is chiefly applicable to double-barrelled guns, in which a greater force is required for the insertion or removal of the two cartridges (or shells) than in the case of a single cartridge, and especially where the shells are out of shape, as above mentioned.

Having now described my invention, what I claim as new and desire to secure by Letters Patent is:

1. In a gun, the combination of a stationary base plate, a movable breech block adapted to slide longitudinally upon said base plate, a locking head containing the striker and rotatably mounted upon said block while being prevented from longitudinally moving relatively to the same, discontinuous threaded parts formed on said head, cooperating discontinuous threaded parts formed on the barrel socket, a control piece adapted to slide longitudinally upon said block, curved grooves and cooperating studs respectively provided on said head and control piece for rotating the former when the latter is shifted on said block and a lever pivoted on said block for operating said control piece and block.

2. In a gun as claimed in claim 1, the provision of means for holding said lever in its operative position when the block is out of its closing position.

3. In a gun as claimed in claim 1, a locking arm connected with said operating lever and adapted to bear upon said base plate for holding said lever in its operative position and an opening in said plate adapted to be engaged by said locking arm, in the closing position of said block and whereby said lever may then be brought into its inoperative position.

4. In a gun as claimed in claim 1, the provision of means for yieldingly and constantly urging said control piece forward.

5. In a gun as claimed in claim 1, the

further feature residing in that each of said grooves comprises a rear rectilinear part parallel with the axis of said head for the purpose set forth.

6. In a gun, the combination of a stationary base plate, a movable breech block adapted to slide longitudinally upon said base plate, a locking head containing the striker and rotatably mounted upon said block while being prevented from longitudinally moving relatively to the same, discontinuous threaded parts formed on said head, cooperating discontinuous threaded parts formed on the barrel socket, a control piece adapted to slide longitudinally upon said block, a number of curved grooves provided on said head, cooperating studs provided on said control piece for rotating said head when said piece is shifted on said block, said studs being further adapted to limit the motion of the striker relatively to said head, and means carried by said block for operating said control piece and block.

7. In a gun, the combination of a stationary base plate, a movable breech block adapted to slide longitudinally upon said base plate, a locking head rotatably mounted upon said block and containing the striker, discontinuous threaded parts formed on the inner wall of the barrel socket, cooperating discontinuous threaded parts formed on said head, means carried by said block for successively rotating said head and shifting said block for closing and opening said barrel, the lower part of said head being provided with a chamfered part adapted to contact with said base plate for the opening position of said head for the purpose set forth.

8. In a gun, the combination of a longitudinally slidable breech block, means for guiding the same, a locking head provided with means adapted to cooperate with means provided on the barrel socket for closing the barrel, said locking head being rotatably mounted upon said block while being prevented for longitudinally moving relatively to the same, a control piece adapted to slide longitudinally upon said block, cooperating means provided on said control piece and locking head, respectively, for rotating the latter when the former is shifted on said block and means carried by said block for operating both said control piece and block.

9. In a gun the combination of a longitudinally slidable breech block, means for guiding the same, a locking head provided with means adapted to cooperate with means provided on the barrel socket for closing the barrel, said locking head being rotatably mounted upon said block while being prevented from longitudinally moving relatively to the same, a control piece adapted to slide longitudinally upon said block, cooperating means provided on said control piece and locking head, respectively, for rotating the

latter when the former is shifted on said block, a lever pivoted to said block, a link connecting said lever to said control piece, and means adapted to prevent said lever from turning unless the locking means provided on the head is substantially in register with the locking means provided on the barrel socket, whereby the same lever may be used for operating both the breech block and the control piece.

10. In a gun as claimed in claim 9 the provision of resilient means for permanently urging said lever into the position corresponding to the closing of the barrel.

15 In testimony whereof I have signed my name to this specification.

JULIEN MARIE PIERRE FAURE.
